UNITED STATES PATENT OFFICE.

ALEJANDRO STEPHENS, OF GUADALAJARA, MEXICO.

STEAM-ENGINE.

SPECIFICATION forming part of Letters Patent No. 624,700, dated May 9, 1899.

Application filed September 13, 1898. Serial No. 690,846. (No model.)

To all whom it may concern:

Be it known that I, ALEJANDRO STEPHENS, of Guadalajara, Mexico, have invented new and useful Improvements in Steam-Engines, 5 of which the following is a full, clear, and exact description.

My invention has for its object to provide a steam-engine which will be simple in construction, reliable in operation, capable of great 10 speed, and economic in the use of steam.

To this end I construct the steam-engine as fully described hereinafter.

The novel features of my invention will be particularly pointed out in the claims.

Reference is to be had to the accompanying drawings, forming a part of this specification, in which similar characters of reference indicate corresponding parts in all the figures.

Figure 1 is a sectional elevation of my im- 20 proved engine on line 1 1 of Fig. 3 with the piston in its lowermost position. Fig. 2 is a similar view with the piston at the end of the upstroke, and Fig. 3 is a side elevation of the engine with part of the cylinder and its cap 25 or shell in section.

A is the frame of the engine, in which is journaled the main shaft B and which carries the cylinder C. In the cylinder is ar- 30 ranged to move the piston D, connected by the piston-rod E and the connecting-rod F to a crank G on the shaft B.

The piston D comprises two parts of different diameters and practically forming two pistons. The inner section D' is fitted to slide 35 upon the outer surface of a central body C', secured at the bottom of the cylinder C. At a point adjacent to the upper end of the section D' when the piston is in its lowermost position the top plate C² of the cylinder and 40 the central body C' are provided with pack- 45 ing-rings H, adapted to engage the piston-section D' upon its inner and its outer surfaces. During its upstroke the piston-section D' moves into a chamber I, formed by an upward extension C³ of the cylinder C. This exten- 50 sion has an opening C⁴ connected to the steam-supply. The outer section D² of the piston is annular and surrounds the cylindrical portion of the piston-section D' at the bottom 55 thereof. This outer section D² moves in the annular chamber I', contained between the cylinder C and the central body or core C'

and must be provided with a packing-ring, such as H'. The extension C³ above the top plate C² is surrounded by a cap or shell J, 55 forming a closed chamber I², which by means of apertures C⁵ in the top plate C² communi- cates with the chamber I'.

The central body or core C' of the cylinder has a partition C⁶ dividing it into a central 60 chamber I³ and an outer annular chamber I⁴ communicating by means of apertures C⁷ in the partition C⁶. The central chamber I³ com- 65 municates at the bottom with the exhaust-pipe K and is open at the top (see Fig. 2) to the cham- 70 ber I⁵, inclosed by the piston-section D' during its upstroke. Near its top the chamber I³ has an annular groove C⁸, into which projects an annular rib C⁹, having apertures C⁰, by means of which the said groove may communicate 75 with the chamber I³ proper. At the bottom the chamber I³ has channels C¹⁰ leading out- 75 wardly into the chamber I'. At the top the chamber I³, or rather the groove C⁸, is in per- 80 manent communication by means of an open- 85 ing C¹¹ with the working chamber I⁵ of high- 90 pressure cylinder D'.

Within the chamber I³ are located two cut- 80 off valves, one of which, L, is double, having two pistons or heads L' L², of which the up- 85 per piston L' controls the passage of steam through the ports C⁰—that is, from the work- 90 ing chamber I⁵ into the receiver formed by the chambers I³ I⁴. The lower head L² is adapted to connect the ports C¹⁰ (and thus 95 the working chamber of the annular low- pressure cylinder) alternately with the ex- 100 haust-pipe K and with the receiver I³ I⁴. The other valve L³ is adapted to move in a guide or small cylinder D³, having apertures D⁴ leading into the space formed by the annular groove C⁸. The top of the piston D' has ap- 105 pertures D⁵, by means of which a communica- 110 tion is established between the steam-cham- 115 ber I and the interior of the cylinder D'. These apertures D⁵ are adapted to be throt- 120 tled by a ring M, seated upon a concave sur- 125 face at the top of the piston D' and capable of turning on said surface with the piston- 130 rod E as its axis. The ring M is pressed 135 downward by a spring N and has radial slots M', adapted to cover or uncover the ap- 140 pertures D⁵. The position of the ring M is con- 145 trolled by a governor O, operated from the

shaft B by bevel-wheels P P' and connected with the ring M by means of a rod Q, a bell-crank lever R, fulcrumed at R', a connecting-rod S, a lever T, fulcrumed at T', and a connecting-rod U, whose ends are connected by ball-and-socket joints with one end of the lever T and with the free end of an arm M², rigidly secured to the ring M.

The cut-off valve L³ for the high-pressure cylinder I⁵ is operated by means of a sleeve V, mounted to slide on the piston-rod E and pivotally connected with rods W, operated by a couple of eccentrics B' on the shaft B. Similarly the valve L' L² for the low-pressure cylinder is operated by the sleeve X, mounted to slide on the sleeve V and connected by rods Y with the eccentrics B² on the shaft B.

It will be seen that the valve L² is an admission and exhaust valve for the low-pressure cylinder, and the valve L' is at the same time an exhaust-valve for the high-pressure cylinder and an admission-valve for the receiver, while the valve L³ is a cut-off valve for the high-pressure cylinder and the ring M forms a variable cut-off, depending upon the speed of the engine.

It will be understood that the relative location of the valves, eccentrics, and crank will be such as to secure the proper timing of the valves, as will be described presently.

When the compound piston is at the end of the downstroke, Fig. 1, steam from the chamber I passes through the slots M' and apertures D⁵ into the cylindrical chamber D³ and through the apertures D⁴ into the groove C⁸, the aperture C¹¹, and the working chamber I⁵ of the high-pressure piston D', thus equalizing the pressure on both faces of said piston. At the same time steam, which during the downward stroke has passed from the high-pressure working chamber I⁵ into the receiver I³ I⁴, is allowed (by an appropriate movement of the valve L²) to pass through the channels C¹⁰ below the annular low-pressure piston D², driving the same upward. Thus during the upstroke only the low-pressure piston is active. The air above the low-pressure piston instead of being compressed within the chamber I' (which would cause a considerable resistance as the piston approaches the top plate C²) is driven out through the apertures C⁵ into the chamber I², and owing to the large area of the two chambers I' I² the degree of compression and the resistance due thereto are only slight. The advantage of having the apertures C⁵ lead into a closed chamber I² instead of making them open into the surrounding air resides in the fact that the body of air passing alternately in and out through the apertures C⁵ remains the same and can have no cooling action on the piston and steam.

As the compound piston finishes the upstroke, Fig. 2, the valve L² is shifted to cut off the receiver I³ I⁴ from connection with the working chamber of the low-pressure cylinder and to connect said working chamber

with the exhaust-pipe K. The pressure is then about equal on both surfaces of the low-pressure piston D². Furthermore, the valve L' is shifted to connect the working chamber I⁵ of the high-pressure cylinder with the receiver I³ I⁴ by means of the opening C¹¹, groove C⁸, and apertures C⁶, so that the exhaust from the high-pressure cylinder passes into the receiver. Finally the valve L³ by moving above the apertures D⁴ cuts the working chamber I⁵ off from connection with the steam-chamber I. There will therefore be a preponderance of pressure on the upper surface of the high-pressure piston D', whether the valve-ring M be in the open position, Fig. 1, or the closed position, Fig. 2. Thus the piston D' will be forced downward. During the downstroke only the high-pressure piston will be active. It will be seen that while each of the pistons is single-acting the engine is double-acting.

The cut-off ring or valve M will, it is understood, become operative only in case the engine exceeds a predetermined speed, when said valve M will cut off steam from the high-pressure working chamber I⁵ during the upstroke before the piston-valve L³ closes the apertures D⁴, and when the valve M closes the openings D⁵ during the upstroke the preponderance of steam-pressure on the upper surface of the high-pressure piston D' will check the upward movement of the piston.

It will be understood that modifications, as long as they remain within the scope of the appended claims, will constitute no departure from the nature of my invention.

Having thus described my invention, I claim as new and desire to secure by Letters Patent—

1. A high-pressure piston, an annular low-pressure piston surrounding the high-pressure piston and rigidly secured thereto, the high-pressure piston having a passage leading from one face thereof to the opposite face, a cut-off valve controlling said passage, a cylinder having two chambers in which said pistons move, a receiver having a valve-controlled connection with the working chamber of the high-pressure cylinder, the low-pressure cylinder having a channel leading to the receiver and to the exhaust, and a valve for opening said channel to the receiver, when the high-pressure piston is at the end of its working stroke, and for connecting said channel with the exhaust when the high-pressure piston is at the end of its inactive stroke, and means for actuating the valves, substantially as described.

2. The combination of the annular low-pressure cylinder, the receiver located centrally within the said cylinder, the high-pressure cylinder located substantially in axial alignment with the receiver, the low-pressure piston movable in the low-pressure cylinder, the high-pressure piston mounted to slide on the outside of the receiver, valves controlling the connections of the receiver with the high-

pressure cylinder and the low-pressure cylinder, and the connection of the latter with the exhaust, substantially as described.

3. The combination of the single-acting cylinder, the piston therein, the cylinder having at one end a channel for the alternate admission and escape of the driving agent, a steam-chamber adapted to communicate with said channel, a valve controlling said communication and a closed chamber in permanent communication with the other end of the cylinder and separated at all times from the steam-receiving end of the cylinder.

4. The combination of the high-pressure cylinder, the low-pressure cylinder, the low-pressure piston, the high-pressure piston having a passage leading from one face thereof to the opposite face, a valve controlled directly from the engine-shaft to close said passage at a predetermined period of the stroke, a variable-cut-off valve carried directly by one of the pistons and likewise arranged to close said passage, a speed-controlled governor operatively connected with said variable-cut-off valve, and connections from the high-pressure cylinder to the low-pressure cylinder, substantially as described.

5. The combination of the high-pressure cylinder, the receiver, the low-pressure cylin-

der, the pistons in said cylinders, the high-pressure piston having a passage leading from one face thereof to the opposite face, and the receiver having passages by which it may communicate with either of the cylinders, a piston-rod connected with one of the pistons, valves controlling said passages and provided with sleeves one of which slides on the piston-rod, while the second valve-sleeve slides on the one first mentioned, and means for actuating the valves, substantially as described.

6. The combination of the high-pressure cylinder and piston, the receiver into which exhausts the motive agent from the high-pressure cylinder, the single-acting low-pressure cylinder, the piston therein, a channel for connecting one end of the low-pressure cylinder alternately with the receiver and with the exhaust, a closed chamber in permanent communication with the other end of said cylinder, but out of communication, at all times, with the steam-receiving end of the low-pressure cylinder, and valves for controlling the admission and exhaust of steam.
